STRIP FEEDING ATTACHMENT

Kenneth P. Morse, Dayton, Ohio, assignor to The
Standard Register Company, Dayton, Ohio, a
corporation of Ohio

Application July 21, 1941, Serial No. 403,311

15 Claims.

(Cl. 197—133)

This invention pertains to strip feeding and aligning devices for manifolding assemblies, and more particularly to a demountable attachment for a writing or imprinting apparatus for advancing superposed strips of continuous series connected printed form stationery past the impression receiving position thereof and arresting the strips with corresponding prescribed record receiving areas thereof in registry with each other and with the imprinting position of such apparatus.

The use of continuous series connected printed form stationery on typewriters, tabulating, bookkeeping and addressing machines and analogous recording apparatus has become quite general. Such writing and imprinting apparatus is ordinarily equipped with frictional feeding means for the record material and a rotary platen about which the stationery is advanced thereby. However, modern commercial requirements, and use of printed form stationery having restricted imprint receiving areas, necessitates positive control of the stationery and its arrest with prescribed areas of superposed stationery strips in exact registry and alignment with each other and with the imprinting position of the apparatus. To facilitate record making operations, it is desirable and advantageous that both the frictional and positive feeding means supplement each other in different stages, and that they be so disposed as not to impede the operation of one by the other.

One of the purposes of the present disclosure is to provide a positive pin type feeding device which is readily applicable to existing machines and apparatus already in use, by which such machines may be adapted to alternate feeding operations.

A further object of the invention is to provide a pin type feeding attachment for writing and imprinting apparatus which is simple and compact in construction, of unitary form, and which may not only be economically manufactured, but will be efficient in use, automatic in operation, uniform in action, have relatively few parts and be unlikely to get out of repair.

A further object of the invention is to provide a positive pin type feeding device which may be bodily removed and re-engaged in operative relation with the writing and imprinting apparatus.

A further object of the invention is to so assemble and arrange the positive pin type feeding device for conjoint use with conventional frictional feeding means embodied in the writing or imprinting apparatus that the frictional feeding means may be employed successively upon the

same manifolding assembly, and wherein the present pin type feeding unit is so disposed that neither the frictional feeding means nor the present pin type feeding device will interfere with nor impede the operation of the other, and will permit ready change from one feeding device to the other, whereby they may conjointly contribute to the strip feeding operation.

A further object of the invention is to provide adjustable record material guiding means by which the path of advancement of the record material may be varied either into or out of relation for engagement by the pin type feeding member.

A further object of the invention is to provide strip feeding means by which the course of the advancing strip may be laterally varied and the device readily adapted to feeding record material of different widths.

A further object of the invention is to provide a strip feeding device having the advantageous structural features and inherent meritorious characteristics and mode of operation herein mentioned.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the accompanying drawings, wherein is shown the preferred but obviously not the only forms of embodiment of the invention,

Fig. 1 is a perspective view of a portion of a typical tabulating machine to which a pin type strip feeding attachment embodying the present invention has been applied.

Fig. 2 is a similar perspective view illustrating a demountable strip feeding unit embodying the present invention being removed from or restored to the imprinting machine.

Fig. 3 is a perspective view of a strip feeding unit disassociated from the imprinting apparatus.

Fig. 4 is a vertical sectional view of a portion of the imprinting apparatus and the strip feeding device mounted thereon, illustrating the course of the record strips to and from imprinting position.

Fig. 5 is a detail view of the driving and motion transmitting mechanism for actuating the feeding device in synchronism with the imprinting apparatus.

Fig. 6 is a top plan view of the mechanism shown in Fig. 5.

Fig. 7 illustrates a modification of the path of travel of the record strips past the imprinting position.

Fig. 8 is a perspective view of a modified form of the strip feeding unit.

Fig. 9 is a vertical sectional view of the form of embodiment of the invention illustrated in Fig. 8.

Like parts are indicated by similar characters of reference throughout the several views.

The installation of the present pin type feeding unit upon a writing or printing machine having conventional frictional record material feeding means enables the material to be advanced past the imprinting position, either positively with superposed plies of material in close registry and alignment with each other and with the imprinting position, or impositively without particular regard to registry and alignment.

There is thus provided optionally selective pin type feeding means and frictional feeding means. Such dual feeding means cooperate with each other, whereby the frictional feeding means may be initially employed until the record material is sufficiently advanced past the record receiving position to be engaged by the present pin type feeding device. By this means it is unnecessary to discard the first form of a strip of stationery as would be the case if the pin type feeding unit alone was utilized and it was necessary to engage the advance end of the record strip with the pin type feeding device in the first instance. This is quite important when using consecutively numbered record forms.

Likewise, when retracting the advanced strips as may be necessary to make corrections, the strips tend to buckle about the platen roll if the pin type device located beyond the platen roll alone is employed. Therefore, the frictional feeding means is effectively used for such purpose and also to hold the record strips in adjusted relation while the advanced portions are disengaged from the pin type feeding device for purpose of making erasures.

Referring to the drawings, 1 is a typical tabulating machine, of which 2 is the platen roll and 3 indicates a series of frictional pressure rollers which are manually adjustable into and out of cooperative relation with the platen roll. Such machines are motor equipped for continuous power operation. Back of the platen roll is the usual paper guide 4 over which the record material 5 is directed beneath and around the platen roll 2. The latter is mounted for bodily swinging movement into and out of operative position, as shown in Figs. 1 and 2. It is to be understood that the tabulating machine 1 is here shown merely for illustrative purposes, and per se forms no part of the present invention, and that the present pin type feeding unit is readily applicable to other recording machines, including typewriters, billing and addressing machines, and analogous mechanisms, and is not, therefore, limited in this respect.

The present unit comprises a unitary frame having relatively spaced end plates 6 interconnected by transverse tie rods 7 and 8, and having journaled therein a transverse shaft 9. The end plates 6 are notched at 10 for detachable interlocking engagement with studs 11 located upon the frame of the imprinting machine 1. The arrangement is such that by oscillating the unit frame upwardly about one pair of studs 11 and

out of engagement with the other studs, the frame may be bodily lifted from the machine.

Mounted upon the transverse rotary shaft 9 is a pair of pin wheels 12, each having a complement of radially disposed spaced pins 13 which are progressively engageable in marginal punched holes 14 in the record material 5. The pin wheels 12 are axially adjustable upon the shaft 9 to vary their relation to accommodate record material of different widths, or to laterally change the path of travel of record material of a given width and effect alignment of prescribed areas with the imprinting position as may be desirable. The pin wheels are preferably, but not necessarily, secured in their adjusted positions by set screws 15 in the pin wheel hubs, which engage in a spline or groove 16 in the shaft 9 and thereby not only lock the wheels in adjusted positions, but also maintain the pins 13 of the respective pin wheels in proper alignment. The shaft 9 and pin wheels 12 are rotated in unison with the platen 2.

At one end thereof inside the end plate 6, the shaft 9 carries a sprocket wheel 17 driven by a chain belt 18 from a corresponding sprocket 19 mounted on the end plate 6 of the frame. The second sprocket 19 is connected to a gear 20 for unison rotation. The gear 20 meshes with an idler pinion 21 mounted on the frame of the imprinting machine, which in turn intermeshes with a driving gear 22 upon the shaft of the rotary platen 2. The arrangement is such that the rotation of the platen roll 2 is transmitted to the shaft 9 and pin wheels 12 thereon, which are of such size that the peripheral speed of the pin wheels and that of the platen roll are substantially equal, and the record material may be advanced by either at the same rate of speed.

The shaft 9 and pin wheels 12 are located above and rearwardly of the platen roll 2, and the record strips 5 after passing about the platen roll and the imprinting position, travel in an upwardly and rearwardly inclined path substantially tangential to the platen roll. To confine the record material to a path substantially tangential to the pin wheels 12, a pair of slotted guide plates 23 are mounted on the transverse tie rod 7 for both lateral sliding and oscillatory adjustment. The guide plates 23 are so disposed that the pins 13 of the wheels 12 project through the slots 24 of the plates into operative engagement in the marginal holes 14 in the strips 5. The guide plates 23 are movable laterally with the wheels 12 to different positions along the shaft 9. When the record material is to be advanced by the frictional feeding means independently of the pin wheels, the guide plates 23 are elevated about their connection upon the tie rod 7 to a position above the path of rotation of the pins 13, whereby the record material is held out of engagement therewith. In order to confine the record material to a path of travel coincident with the guide plates 23, slotted retainer arms 25, which like the said guide plates, are mounted on the tie rod 7 for to and from sliding adjustment and for oscillatory motion thereabout. When in their adjusted positions, both the guide plates and the retainer arms are secured upon the tie rod 7 by set screws 27. When in normal operative position, the retainer arms 25 overlie the guide plates 23 with their slots 26 in registry with the slots 24 of the guide plates. The pins 13 of the pin wheels 12 project through the guide plate slots 24 and thence through the marginal holes 14 in the record material and into the slots 26 of the retainer arms 25.

Interconnecting the end plates 6 of the frame beneath the pin wheels 12 is an arcuate guard plate or pan 28 which prevents interference of the incoming record material and the bottoms of the pin wheels, and also provides a stop or rest against which the free ends of the record material guides 23 engage when in position to enable the material to be fed by the pin wheels 12. Mounted on the transverse tie rod 8 beneath the guard plate 28 are laterally adjustable fingers 29 secured in adjusted position by set screws 30, by which the incoming record material is confined to a prescribed path of travel.

The overlying strip retaining arm 25 is provided with a terminal enlargement or lug 31 engageable with the guide plate 23 beyond the margin of the record material to hold the retainer in spaced relation sufficient to permit free movement of the record material intermediate the guide plate 23 and retainer arm 25.

Instead of directing the incoming record material over the usual paper guide 4, it may be more desirable and convenient to direct the record material supply beneath the paper guide, as shown in Fig. 7.

In Fig. 8 is illustrated a modification wherein a single continuous slotted record material guide plate 23a performs substantially all the functions and serves approximately all purposes of the separate laterally adjustable strip guides 23. The plate 23a of Fig. 8 extends approximately the full width of the feeding unit frame and like the separate guide plates 23 is pivoted upon the transverse tie rod 7 for oscillatory adjustment, and when in operative relation with the pin wheels the guide plate rests upon the margin of the guard pan 28. The record material guide plate 23a is slotted at spaced intervals at 24a to enable the pin wheels 12 to be variously positioned to accommodate material of different widths, or to enable the material to be directed in different paths of travel. To enable the strip retainer arms 25 to be laterally adjusted relative to the continuous plate 23a to accommodate material of different widths, the hold down or retainer arms are mounted for lateral shifting and oscillatory motion on a separate transverse rod 1a parallel with the tie rod 7 upon which the guide plate is mounted.

Fingers 32 attached in spaced relation to the outer faces of the end plates 6 of the frame engage in straddle relation with the side frames of the writing or imprinting apparatus to detachably hold the frame in its operative position thereon.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A strip feeding apparatus for a writing or imprinting machine, a frame including side plates engageable with the writing or imprinting machine, tie rods interconnecting the side plates, a revoluble shaft mounted in the side plates, a pin wheel on the revoluble shaft and engageable in longitudinally spaced holes in continuous strips of record material to be advanced past the impression receiving position of the machine, a slotted guide plate for the record material pivotally mounted on the frame in overlying relation with the pin wheel, through the slot of which the pins of said pin wheel project into engagement with the record material, said guide plate being adjustable to direct the record material past the pin wheel without engagement thereby, and a retaining member also pivotally mounted on the frame and extending into overlapping relation with the slotted guide plate between which retaining member and the guide plate the record material is advanced, a guard member supported on said frame beneath the pin wheel and preventing interference of the pin wheel with incoming record material, and lateral guide members upon a tie rod beneath the guard between which the incoming record material advances for directing the incoming record material into position to be subsequently engaged by the pin wheel.
2. A strip feeding attachment for a writing or imprinting machine, including a frame comprising side plates engageable with the writing or imprinting machine and interconnected into a unitary structure, configurations thereon for detachable engagement with the machine, a rotary shaft mounted on said side frames, a pin wheel axially adjustable on said shaft and engageable in longitudinally spaced holes in a strip of record material to be advanced past a legend receiving position of said machine, a slotted guide for the record material adjustably mounted on the frame for to and fro lateral adjustment, through the slot of which the pins of said pin wheel project into engagement with the record material, said slotted guide being adjustable into and out of intersecting relation with the pin wheel, additional to its lateral adjustment to optionally guide the record material into or out of engaging relation with the pin wheel.
3. A strip feeding attachment for a writing or imprinting machine, including a supporting frame detachably mounted on the machine, a rotary shaft, driving means therefor actuated by the said machine, a pin wheel on said rotary shaft, a rearwardly and upwardly extending guide plate for record material overlying the pin wheel through the slot of which the pins of said pin wheel project into engagement with the record material, said guide plate being adjustable to and from the pin wheel in a direction parallel to the plane of rotation thereof whereby said guide plate may be made to direct the record material in a path wherein it is engaged by the pin wheel or alternatively in a path beyond the range of operation of the pin wheel wherein it is not engaged thereby, and a retaining member overlying the slotted guide in its different positions of adjustment.
4. A strip feeding attachment for a writing or imprinting machine, including a frame detachably engageable with the machine, a revoluble shaft mounted therein, driving means for actuating the shaft in synchronism with the actuation of the machine, a pin wheel on said shaft

and engageable in longitudinally spaced holes in a length of record material, an arcuate plate extending transversely of the attachment in substantially concentric relation with the pin wheel and fixedly attached to the frame within which the pin wheel operates and beneath which the incoming record material passes, thereby preventing interference of the pin wheel with such incoming record material, a guide rod in said frame beneath the arcuate plate over which the incoming record material is advanced and lateral stops on said rod substantially coincident with the margins of the incoming record material directing the record material into position to be subsequently engaged by the pin wheel.

5. A record material feeding attachment for a writing or imprinting machine having a rotary platen roll, including a frame supportable upon the machine, an axially adjustable pin wheel mounted therein in elevated rearwardly disposed relation with the platen roll of the machine, an upwardly and rearwardly inclined slotted guide plate mounted on the frame for both oscillatory and lateral bodily shifting movement, and an adjustable retainer member overlying the guide plate, the pin wheel, guide plate and retainer member being adjustable transversely of the path of travel of the record material to accommodate material of different widths or differently disposed relative to the machine, and driving means for actuating the pin wheel in synchronism with the rotation of the machine platen.

6. A record material feeding attachment for a writing or imprinting machine having a platen roll, including a frame supportable upon the machine, a pin wheel mounted in said frame in elevated rearwardly offset relation with the platen roll in the direction of advancement of the record material, a rearwardly and upwardly inclined guide plate for the record material disposed in substantially tangential relation with the pin wheel through the slot of which the pins of said pin wheel may project into engagement in longitudinally spaced feed holes in the record material, and a pivotal mounting about which the slotted guide plate is capable of oscillatory adjustment to direct the record material into the range of action of the pin wheel or beyond such range at the will of the operator, locking means for maintaining the slotted guide plate in its adjusted relation with the pin wheel and driving means for actuating the pin wheel by actuation of the machine.

7. A record material feeding attachment for a writing or imprinting machine having a platen roll, including a frame supportable upon the machine, a pin wheel mounted in said frame in elevated rearwardly offset relation with the platen roll in the direction of advancement of the record material, a rearwardly and upwardly inclined slotted guide plate for the record material disposed in substantially tangential relation with the pin wheel through the slot of which the pins of said pin wheel may project into engagement in longitudinally spaced feed holes in the record material, said slotted guide plate being adjustable relative to the pin wheel in a direction parallel to the plane of rotation of the pin wheel to thereby optionally guide the record material into or out of engaging relation with the pin wheel, and driving means for actuating the pin wheel in synchronism with the machine.

8. A record material feeding attachment for a writing or imprinting machine having a rotary

platen roll about which the record material is advanced, an axially adjustable pin wheel mounted on said frame in elevated rearwardly offset relation with the platen roll in the direction in which the record material is advanced, an upwardly and rearwardly inclined slotted guide plate disposed in substantially tangential relation with the pin wheel having therein a plurality of upwardly and rearwardly directed relatively spaced parallel slots through either one of which the pins of said pin wheel may be projected into engagement in spaced holes in the record material by relative axial adjustment of the pin wheel, a pivotal mounting for the guide plate on said frame about which the plate is capable of oscillatory adjustment to guide the record material into or beyond the range of action of the pin wheel at the will of the operator, said pin wheel being axially adjustable relative to the slotted plate to enable engagement of the pin wheel with the record material through either one of a plurality of said slots, a retainer member overlying the pin wheel in its different positions of adjustment and maintaining operative engagement of the record material with the pin wheel, and driving means for actuating the pin wheel by operation of the machine.

9. A record material feeding apparatus for a writing or imprinting machine having a platen roll about which the record material is advanced, a pin wheel mounted in elevated relation above and offset relative to the platen roll in the direction of advancement of the record material, a record material guide member inclined upwardly and rearwardly in a plane substantially tangential to the pin wheel, beyond the plane of which the pins of the pin wheel project into feeding engagement in longitudinally spaced holes in the record material, and a pivotal mounting for the guide member about which the guide member is swingingly adjustable in a plane parallel to the plane of rotation of the pin wheel by which the record material may be directed optionally into engaging relation with the pin wheel or through a path wherein the record material avoids engagement with the pin wheel.

10. An attachment for a writing or imprinting apparatus wherein record material is advanced about a rotary platen roll and past an imprinting position, including a pin type feeding device for advancing the record material about the platen roll and past the imprinting position and thence substantially tangential to the platen roll, including a frame comprising end plates detachably engageable with the frame of the writing or imprinting apparatus, spaced transverse tie rods interconnecting the end plates, a transverse shaft pivoted in the end plates, a pair of pin wheels mounted on said shaft, an upwardly and rearwardly inclined guide plate pivotally mounted on the frame by which the advanced portion of the record material is supported during advancement and by which it is directed, said guide plate being normally disposed in substantially tangential relation with the pin wheels and movable thence to a position above the pin wheels, and having plural slots therein through different slots of which the peripheries of the pin wheels may optionally project, and adjustable slotted retainer arms overlying the slotted guide plate and movable relative thereto into registry with different slots of the plate.

11. A record material feeding attachment for a writing or imprinting machine having a platen roll, including a frame supportable upon the ma-

chine, a pin wheel operable by rotation of the platen roll mounted in said frame in elevated rearwardly offset relation with the platen roll in the direction of advancement of the record material, a rearwardly and upwardly inclined slotted guide plate by which the record material is supported and guided in substantially tangential relation with the pin wheel through the slot of which the pins of said pin wheel may project into engagement in longitudinally spaced feed holes in the record material, a support upon which said slotted guide plate is adjustably mounted for movement relative to the pin wheel to optionally guide the record material within range of operation of the pin wheel or beyond such range of operation at the will of the operator, and means for retaining said slotted guide plate in its adjusted position.

12. A record material feeding attachment for a writing or imprinting machine, having a platen roll about which the material is advanced, including a supporting frame mountable upon the machine, a rotary pin wheel mounted on said frame, an upwardly and rearwardly inclined slotted guide for the record material disposed in substantially tangential relation with the pin wheel through the slot of which the pins of said pin wheel may project into feeding engagement in holes in the record material, a guard beneath the pin wheel substantially concentric therewith, and driving means for rotating the pin wheel in unison with actuation of the platen roll of the machine.

13. A record material feeding device for a recording apparatus, including a movable pin type feeding device engageable in longitudinally spaced holes in a length of recording material for progressively advancing the record material past a recording position, a pair of overlapping

guide members between which the record material is advanced, and through a slot in one of which the pin type feeding device projects into operative engagement with the record material, 5 at least one of said guide members being pivoted for swinging movement into and out of operative relation with the pin type feeding device in a plane substantially parallel with the path of movement of the record material.

10 14. A record material feeding device for a recording apparatus, including a movable pin type feeding device engageable in longitudinally spaced holes in a length of recording material for progressively advancing the record material past a recording position, a guide member therefor relative to which the record material is advanced, and a laterally offset pivotal connection for the guide member from which the guide extends in lapping relation with the record material 15 and about which the guide is swingingly adjustable in a plane parallel with the direction of movement of the record material.

15 16. A record material feeding device for a recording apparatus, including a movable pin type feeding device engageable in longitudinally spaced holes in a length of recording material for progressively advancing the record material past a recording position, a pair of guide members disposed in overlapping relation with each other and with the record material which is advanced therebetween, and offset hinge connections for the guide members beyond the margin of the record material being advanced therebetween, about 20 which the guide members are independently adjustable through swinging movement in a plane parallel with the direction of travel movement of the record material.

KENNETH P. MORSE.
